AIR CLEANING APPARATUS

Henry C. Lambert and Squire E. Garnsey, Toledo,
Ohio, assignors to The De Vilbiss Company,
Toledo, Ohio, a corporation of Ohio

Application August 5, 1937, Serial No. 157,509

1 Claim. (Cl. 91—60)

This invention relates to air cleaning apparatus for use particularly in connection with spray booths, to remove from the exhaust air, paint, lacquer and other foreign matter entrained therein as a result of spraying operations.

It is found in practice that exhaust air moving at a high velocity gathers the overspray from the spray gun much more efficiently than with a slow moving column of air, and also that the cleaning action is more efficient in the former case than in the latter.

The object of the invention is to so act on the air in its passage through the outlet throat and the expansion and eliminating chambers as to cause a material acceleration of the air current by a restriction and immediate expansion thereof, and to cause the air during such action to pass through a liquid spray, such as water with a saponifying agent therein, whereby a thorough, rapid and efficient cleaning of the air is effected.

20 A further object of the invention is the provision of means in the rear of a spray booth, whereby liquid used to clean the exhaust air is captured after the cleaning operation and caused to flow over and wash down the inner rear wall surface of the spray booth and efficiently and economically prevent the accumulation thereon of paint or other material being sprayed. This means also provides a liquid curtain through which the exhaust air from the booth passes.

Other objects and advantages of the invention will be apparent from the following detailed description thereof, and from the accompanying drawings, in which—

Figure 1 is a side elevation of an apparatus embodying the invention, with parts broken away; Fig. 2 is an enlarged vertical section of a part thereof, and Fig. 3 is a front elevation of the apparatus, with parts broken away.

Referring to the drawings, 1 designates a room or compartment containing the air to be cleaned and which, in the present instance, comprises part of a booth commonly used in paint spraying work.

At the rear side of the booth or compartment 1 is a housing 2 in which the cleaning of the exhaust air from said compartment takes place. In the bottom portion of the housing 2 is an open top tank 3 containing a cleaning liquid 4 which may preferably but not necessarily constitute water with a saponifying agent therein. Above the tank 3 and in the rear portion of the housing is an exhaust throat passage 5 opening at its top into an expansion chamber 6 in the top portion of which are located a series of elimi-

nator or baffle plates 7 forming a plurality of zigzag upwardly extending passages 8. The air, after passing through the eliminator passages 8, enters a blower chamber 10 at the top of the housing and is then discharged by the blower 11. 5 The action of this blower is such as to create a strong draft from the booth and through the cleaning apparatus.

Between the tank 3 and floor plate 12 of the expansion chamber 6 in advance of the throat 10 passage 5 is a space 13 which is open at its front side to the booth chamber 1 and forms a part thereof.

The throat passage 5 is of rectangular form in cross-section, being narrow in one direction and 15 broad in the other, and communicates at its lower end with the space 13, and between such point of communication and the expansion chamber 6 it has a slot-like Venturi restriction formed by the opposed upwardly extending inwardly inclined plates 15 and 16 which, immediately above the point of greatest restriction of the passage, diverge outwardly on an incline relative to the passage to permit expansion of the air in its upward passage through the throat. The cleaning 20 liquid is discharged in spray-form into the restricted portion of the throat passage from a plurality of nozzles 18 on a pipe 19 which has connection through a pump 20 with the liquid in the tank 3, so that liquid may be drawn from the 30 tank and forcefully discharged from the nozzles into the throat passage. The nozzles 18 are disposed within the throat passage 5 above the Venturi restriction thereof and have a conical spray discharge downwardly in the passage, the 35 spray cones being adapted to overlap each other and also to overlap the upper restricted edge portions of the plates 15 and 16, so that all portions of the restricted portion of the throat passage are covered by the spray. This causes all of 40 the air in its passage through the throat to pass through the liquid spray and to carry a considerable portion of the spray therewith. In practice, the spray nozzles are placed about six inches apart throughout the length of the portion of the 45 pipe 19 within the throat passage.

The wall between the throat 5 and chamber 13 is formed by two spaced parallel plates 21, the outer one of which has a plain outer side exposed to the chamber 13 while the inner plate 50 carries at its inner side the passage restricting plate 16. The plates 21 are connected at their lower edges and near their upper edges by webs 21a, the upper of such webs cooperating with the upper end portions of the inner and outer plates 55
